LOCK GUARD

Fred A. Trachsler, Vallejo, Calif.

Original application April 24, 1950, Serial No. 157,715, now Patent No. 2,631,881, dated March 17, 1953. Divided and this application October 21, 1952, Serial No. 315,969

3 Claims. (Cl. 292—346)

This invention relates to a lock guard.

This application is a division of my copending application Serial No. 157,715, filed April 24, 1950, now United States Patent No. 2,631,881.

It is a rather common practice for criminals to open locked doors by means of a sheet of thin material such as isinglass, Celluloid or the like by slipping the sheet between the jamb and door and against a cam-type lock bolt in order to force the bolt open and thus release the lock to obtain entry. The present invention provides a means to prevent the use of such an implement to effect opening of locked doors and the same is an object of this invention.

Another object is to provide apparatus for the prevention of opening of locked closures by means of an improved strike plate normally affixed to the door jamb.

Further objects of the present invention are to provide improved hardware for locking mechanisms for the purposes above set forth and which is inexpensive and simple to manufacture and install and which will not interfere with the normal operation of the closures and which effectively prevents unlawful and undesired opening of locked closures.

Further objects of the present invention will become apparent upon reading the following specification and referring to the accompanying drawings in which similar characters of reference represent corresponding parts in each of the several views.

In the drawings:

Fig. 1 is a perspective view of a fragmentary part of a closure jamb equipped with the present invention.

Fig. 2 is a horizontal sectional view of a door and jamb equipped with the present invention and showing a sheet of thin material, such as Celluloid, trapped in the guard.

Fig. 3 is a front elevation of the lock guard.

Fig. 4 is an end elevation thereof.

As illustrated and described herein, the present invention is arranged to be attached to a conventional door jamb and is useable with conventional lock hardware particularly wherein the bolt of the lock is provided with a cam face. It will be understood, however, that the guard might with equal facility be carried by the door rather than the jamb.

The device is illustrated in Figs. 1 through 4 and com-

2

prises a plate, such as a strike plate B, carried by a door jamb C provided with an aperture 2 to receive a lock bolt D which is indicated as provided with a cam face 4. The bolt is carried by a door A. The jamb C, as illustrated, is provided with a conventional door stop E. The door strike B may be of conventional design and is bifurcated at its margin and provided with flanges 13 and 14, with a recess 16 therebetween. The strike plate, having a marginal bifurcation at top, bottom and rear, may be affixed to the jamb so that the rear bifurcation is adjacent to the stop E. The groove or recess 16 extends continuously in a U-shaped fashion around the strike plate and surrounds the bolt-receiving aperture 2. The flange 13 is larger than the flange 14 which lies against the jamb C.

Fig. 2 illustrates a "jimmy" sheet G formed of Celluloid or the like inserted between the door stop and jamb and indicates how the sheet is trapped in the groove or recess 16, thus preventing the sheet from bearing against the same face 4 of the bolt D to force the bolt open.

It is noted that the flange 14, lying against the jamb, is less than the width of flange 13 and thus the sheet G is trapped between flange 13 and flange 14 in the recess 16 or between flange 13 and the jamb.

The invention has been illustrated and described in specific detail of use and installation for purposes of clarity of understanding and it is intended that various changes in use, design, and installation may be practiced within the spirit of the invention and scope of the appended claims.

I claim:

1. A lock guard for use to prevent opening of a cam-type bolt by insertion of a pliable strip between the door and jamb from the stop side of the door comprising a rigid, substantially flat strike plate for said jamb apertured for reception of a lock bolt and formed with its side edge adapted to be positioned nearest the stop and grooved to form parallel flanges with a recess between said flanges, said recess being arranged to intercept a pliable strip and extending adjacent said bolt, one of said flanges being adapted to lie close against said door in the vicinity of said bolt between said bolt and said stop.

2. A guard according to claim 1 in which the edge of said guard is grooved at top and bottom similar to the groove on its side edge.

3. A guard according to claim 2 wherein the flange nearest said door is wider than the flange nearest said jamb.
